UNITED STATES PATENT OFFICE.

LILY FAY WILMERDING, OF FLUSHING, NEW YORK.

APPARATUS FOR COMPRESSING GARBAGE AND OTHER MATERIALS.

1,160,352.

Specification of Letters Patent.

Patented Nov. 16, 1915.

Application filed November 14, 1914. Serial No. 872,206.

To all whom it may concern:

Be it known that I, LILY FAY WILMERDING, of Flushing, in the county of Queens and State of New York, have invented certain new and useful Improvements in Apparatus for Compressing Garbage and other Materials, of which I do declare the following to be a full, clear, and exact description, reference being had to the accompanying drawings, forming a part of this specification.

Figure 1 is a perspective view of my improved apparatus. Fig. 2 is a view partly in front elevation and partly in vertical section. Fig. 3 is a detail view in horizontal section on line 3 of Fig. 2, showing one of the slide plates and the open work bottom of one of the press cans partially withdrawn. Fig. 4 is a view in central vertical section on line 4 of Fig. 2, parts being shown in elevation. Fig. 5 is a view in vertical section on line 5 of Fig. 2. Fig. 6 is a view similar to Fig. 3 but showing the slide plate closed and one of the press cans partially moved to position above the plunger head of the press.

The present invention, while applicable in whole or in part to other uses, is designed more particularly to provide an improved press for kitchen garbage and like material.

It has heretofore been customary to throw kitchen garbage, ashes, bones, and similar refuse, as fast as it accumulates, indiscriminately into a common receptacle located in the kitchen, the yard, or the alley, as the case may be, to await the coming of the garbage collector. Much of the garbage, if not decayed, soured or mixed with bones, cans, etc., would have value for feeding pigs, poultry, etc., but when left to stand in the usual way, its moisture causes fermentation and decay, flies breed, germs multiply, and stenches and disease result. The collection of such filthy stuff is a nuisance, attended with smells and dust, and requiring a large force of men and wagons, a dumping ground, etc.

The object of my present invention is to provide an improved apparatus that may be conveniently located in the kitchen or in like accessible position, whereby the useful portions of the garbage may be immediately separated from the useless and refuse portions, whereby the moisture may be pressed out of the garbage, thereby reducing to a

very material extent the volume of the stuff to be collected, and whereby the compressed garbage can be conveniently retained as it accumulates until the collector arrives to remove it.

To this end, my invention consists in the novel apparatus hereinafter described, illustrated in the accompanying drawings and particularly pointed out in the claims at the end of this specification.

While I shall describe in the following specification what I regard as the preferred embodiment of my invention, I wish it distinctly understood that the details of the invention may be varied within wide limits without departing from its scope, and that features of the invention may be employed without its adoption as an entirety.

As illustrated in the accompanying drawings, my invention is shown as comprising a base A that may consist of bars having downwardly bent legs a, these bars being conveniently bolted together, as by a cross plate 10. Upon the base A will rest the cans or receptacles B and B', adapted to receive, respectively, the useful and the useless or refuse garbage—that is to say, one of these cans will receive the garbage that is suitable for use as food for pigs, poultry, or the like, while the other can B' will receive the garbage or refuse that is not adapted for such food purposes. Each of the cans B and B' is shown as provided, adjacent its top, with a handle b, whereby it may be conveniently moved.

From the base A rises the front and rear standards 11 and 12 that are connected at their top by a cross bar 13. Between these standards 11 and 12, and conveniently bolted thereto as at c, is secured a horizontally disposed frame C, preferably of sheet metal. The lower portion of this frame is formed as a pan C', into which will flow the liquid that is extracted from the garbage, and from the bottom of the pan C' the liquid will be conducted away by a pipe C² to the sewer, drain pipe, or to a pan 15 (see Fig. 4) set beneath the stand A. Within the pan C are formed several openings 20, 21 and 22, these openings being surrounded by flanges which rise from the bottom of the pan C'. Projecting forwardly from the walls of the frame C are the flanges or rails 23 and 24 that may be formed integral with the body of the frame, as clearly shown in Fig. 3 of the drawing. These flanges or rails 23

and 24 serve as supports for the press cans or receptacles D and D'. Preferably, these press cans or receptacles D and D' are formed of sheet metal and at their bottoms they are provided with outwardly turned flanges 25 and 26 adapted to rest upon the rails or flanges 23 and 24 of the frame C. Each of the press cans D and D' is open both at the top and bottom, the top of each can being preferably furnished with a lid or cover d which, if desired, may be hinged to the body of the can as at d'. As shown, the bottom of each of the cans D and D', is formed with inwardly turned side flanges d², the purpose of which will presently more fully appear.

In the front wall of the frame C are formed longitudinal slots through which pass the slide plates E and E', each of these plates being adapted to be shifted by its perforated front end e into position beneath its respective cam D or D'. The slide plates E and E' are preferably formed of sheet metal and these slide plates rest upon the flanges that surround the openings 20 and 21 formed through the pan C'. Preferably, the upper edges of these flanges 20^a and 21^a are formed with outwardly turned edges or flanges 27 that will be engaged by downwardly turned flanges e³ (see Fig. 2) formed on the under side of the slide plates E and E'. To the bottom of each of the slide plates E and E' are attached depending stops e⁵ that serve to limit the inward movement of the slide plates by contacting with the front of the frame C. Upon the upper surface of each of the slide plates E and E' (these plates being duplicates one of the other) are mounted the guide flanges e⁶ (see Fig. 5) adapted to engage the downwardly turned flanges f on the under side of the reticulated or open work diaphragms F, one of which extends beneath each of the press cans D, D'. If desired, a vertical flange e⁸ may be provided adjacent the front of each of the side plates E and E'.

The press cans D and D' rest upon the flanges 23 and 24 in position normally above the corresponding openings 20 and 21 in the pan C' and when in such position, the bottoms of these press cans are normally closed by the diaphragms F. These press cans, when in normal position, are above the corresponding cans or receptacles B and B'. When in the position shown in Figs. 1 and 2 of the drawings, the press cans D and D' are interlocked with their respective diaphragms F by the engagement of the inwardly turned flanges d² at the bottom of the press cans with the edges of diaphragms F, as clearly shown in Fig. 2; so that when the press cans are shifted laterally above the press, as will presently be described, the diaphragms F will be carried with the press cans. When, however, the press cans are

returned to normal position above their respective openings 20 and 21, the diaphragms F being interlocked with the flanges e⁶ on the slide plates E and E', the withdrawal of the slide plates through the openings in the front of the frame C will withdraw the diaphragms from beneath the press cans so as to permit the contents of these cans to drop into the subjacent cans B and B'.

Through the opening 22 in the pan C' (see Fig. 4) passes the stem or plunger G of a press, the head G' of this press being rigidly secured to the upper end of the stem or plunger G. Preferably, the head G' is formed with a corrugated upper plate g of a width, from front to back, corresponding to the distance between the downwardly turned flanges f of the diaphragm F. Hence, it will be seen that when either of the press cans D' is shifted from the normal position shown by full lines to the central position shown by dotted lines in Fig. 2 of the drawings, not only will the diaphragm F be moved over the head G' of the press, but the flanges f of the diaphragm will interlock with the front and rear edges of the head G' of the press, as clearly shown in Fig. 4 of the drawings. The press may be of any suitable or convenient form. Preferably, I employ a "jack-press" of familiar construction. As shown, this press comprises a vertical frame H that is bolted at its bottom to the base A, and through the body of this frame passes the plunger G. The body H of the press is straddled by a yoke K that is pivoted, as at k, to the body H, and to the inner end of this yoke K is pivotally connected a link 30 that engages at its upper end with a cramping sleeve 31 (see Fig. 4). Through an arm 32 projecting upwardly from the top of the body H of the press, extends an arm 33 projecting from a cramping sleeve 34 through which the plunger G passes. The pivoted yoke K is provided at its outer end with a socket to receive the operating handle K'. When the handle is forced downward, the plunger will be raised by the shifting of the cramping sleeve 31 through the medium of the yoke K and link 30, but the downward movement of the plunger will be checked as the handle K' moves upward, by means of the sleeve 34, in a manner well understood. When the plunger has been moved as high as desired and the garbage has been thoroughly compressed, the plunger may be released and permitted to drop downward to its lowermost position by raising the handle K' to its highest position, at which time a shoulder k² on the yoke K will engage the cramping sleeve 33 and shift this sleeve so that it will no longer cramp the plunger but will permit it to drop.

From the foregoing description, the operation of my improved apparatus, when

used for the treatment of garbage, will be seen to be as follows: The press cans D and D' will be conveniently marked to indicate the character of the garbage which they are 5 adapted to receive, and the subjacent cans B and B' may also be correspondingly marked. Into one of the cans D will be placed all garbage that is adapted for food purposes, such as potato or fruit parings, 10 scraps of bread, meat or the like, while into the other can will be placed garbage that is not adapted for that purpose, such as egg shells, coffee grounds, skins of citrus fruits, spoiled food, or the like, but which is 15 adapted to be compressed. It will be understood that garbage such as bones, tin cans, or the like, will be dropped into the lower can beneath the can that receives the useless garbage. When a sufficient quantity 20 has accumulated in either of the press cans, such can will be moved from its normal position to a central position above the head G' of the press, and beneath the cross bar 13. If desired, a thumb-screw 13^a may 25 pass through the cross bar 13 to bear upon the lid of the can during the operation of the press. When the press can has been thus brought to central position, the operating handle K' will be reciprocated and the 30 press head will be caused to rise and compress the garbage within the can above it. The liquid from the garbage will flow down through the diaphragm F onto and around the press head G' and into the pan C', 35 whence it will be conducted away by the discharge pipe C². After the garbage has been thoroughly compressed (and it should remain under the press a sufficient time to permit the liquid to escape), the head G' of 40 the press will be dropped, after which the can will be shifted laterally to normal position, carrying with it the diaphragm F. The diaphragm F may then be withdrawn 45 from beneath the press can D by pulling outward the slide plate E, as the slide plate and diaphragm are interlocked (in the manner above described) when the press can is 50 in position above the slide plate. As the slide plate E and diaphragm F are thus withdrawn from the opening in the front of the frame C, the compressed garbage within the press can is allowed to drop into the corresponding cans B or B' beneath it. Of course, should the compressed garbage 55 stick within the press can after the diaphragm F has been withdrawn, it may be readily forced out through the open bottom of the press can and caused to fall through the corresponding opening 20 or 21 of the pan C'. After the compressed garbage has 60 thus been discharged, the diaphragm F and slide plate E will be restored to normal position, thereby closing the bottom of the press can and adapting it to receive additional garbage. 65

By means of my improved press, not only is a convenient means afforded for separating the useful from the useless garbage, but the mass of garbage is so reduced in volume that the expense incident to its removal is 70 very materially lessened. So, also, the many objections incident to the ordinary garbage cans are entirely overcome.

The feature of employing an upwardly moving press plunger for extracting the 75 moisture from the garbage is an important one, as it not only enables the liquid to be much more readily removed than would be possible with a press acting upon the top of the garbage, but such a press plunger can 80 be more conveniently disposed in a manner permitting a plurality of cans to be shifted over the plunger head.

My invention will be found to possess many other advantages which will be readily 85 understood by those familiar with the inconvenient and objectionable features incident to existing methods of garbage disposal.

I claim as my invention:—

1. An apparatus of the character described, comprising a plurality of upper press cans, a plurality of lower cans or receptacles located beneath said press cans, an intermediate support for said upper press 95 cans through which support material may be discharged, removable bottoms for the press cans, and a press having a plunger head to and from which the press cans may be shifted.

2. An apparatus of the character described, comprising a plurality of upper press cans, a plurality of lower cans or receptacles located beneath said press cans, an intermediate support for said upper press 105 cans through which support material may be discharged, removable bottoms for the press cans, and a liquid receptacle for catching the liquid expressed from the press cans.

3. An apparatus of the character described, comprising a plurality of upper press cans, a plurality of lower cans or receptacles located beneath said press cans, an intermediate support for said upper press 110 cans through which support material may be discharged, removable bottoms for the press cans, and a press having a plunger head located between the press cans and to and from which the press cans may be shifted.

4. An apparatus of the character described, comprising a plurality of upper press cans open at their lower ends and provided with vertically movable diaphragms, a press having a plunger head to and from which the press cans may be shifted, a support for said press cans, means for detachably engaging said diaphragms with said plunger head when the press cans are moved opposite said plunger head, and means for withdrawing said diaphragms from beneath 125

the press cans when the latter are shifted to normal position.

5. An apparatus of the character described, comprising a press, a downwardly extending plunger, a liquid receiving pan extending about said press and having an opening to receive the downwardly extending plunger of said press, a press can open at its bottom and movable over and away 10 from the plunger of the press, an openwork diaphragm for said press can, and means for actuating said plunger.

6. An apparatus of the character described, comprising the combination with a 15 press having a plunger head and a plunger extending downwardly therefrom, of a press can, an openwork diaphragm for said press can, means for closing the top of said press can, means for interlocking said diaphragm 20 with the press can as the latter is shifted, and means for engaging the diaphragm of the press can with the plunger head when the press can is shifted over the plunger head.

25 7. An apparatus of the character described, comprising the combination with a press having a plunger head and a plunger extending downwardly therefrom, of a pan and supporting frame adjacent said plunger head, a press can slidably mounted upon

said supporting frame, said supporting frame being provided with means to engage the top of the can when the latter is in position above the plunger head, an openwork diaphragm for said press can, means whereby the press can shall engage said openwork diaphragm when said press can is shifted, and means for withdrawing said openwork diaphragm from beneath the press can to permit the discharge of compressed material 35 therefrom.

8. An apparatus of the character described, comprising the combination with a press, of a plurality of press cans for receiving materials of different kinds, said 45 press cans being movable above and away from the plunger of said press, means for closing the upper ends of said press cans, openwork diaphragms for said press cans, means whereby said openwork diaphragms 50 are shiftable with said press cans over and away from the plunger of said press, and means for removing said openwork diaphragms from beneath the press cans to permit the discharge of pressed material therefrom.

LILY FAY WILMERDING.
